US00D592211S

(12) **United States Design Patent**
Ichise et al.

(10) **Patent No.:** US D592,211 S
(45) **Date of Patent:** ** May 12, 2009

(54) **MOBILE INFORMATION TERMINAL**

(75) Inventors: **Kentaro Ichise**, Tokyo (JP); **Taihei Miyaji**, Tokyo (JP); **Katsuaki Shimizu**, Saitama-ken (JP)

(73) Assignee: **Kabushiki Kaisha Toshiba**, Tokyo (JP)

(**) Term: **14 Years**

(21) Appl. No.: **29/321,339**

(22) Filed: **Jul. 15, 2008**

(51) LOC (9) Cl. **14-02**

(52) U.S. Cl. **D14/346**; D14/345

(57) **CLAIM**

The ornamental design for a mobile information terminal, as shown and described.

DESCRIPTION

FIG. 1 is a bottom, front and right side perspective view a mobile information terminal showing our new design,

FIG. 2 is a bottom, front and right side perspective view showing an article in an opened position thereof,

FIG. 3 is a front elevational view thereof,

FIG. 4 is a rear elevational view thereof,

FIG. 5 is a left side elevational view thereof,

FIG. 6 is a right side elevational view thereof,

FIG. 7 is a top plan view thereof,

FIG. 8 is a bottom plan view thereof,

FIG. 9 is a front elevational view showing the article in the opened position thereof; and,

FIG. 10 is a right side elevational view showing the article in the opened position thereof.

1 Claim, 5 Drawing Sheets
